UNITED STATES PATENT OFFICE

TORCUATO DI TELLA, OF BUENOS AIRES, ARGENTINA

PUMP FOR THE DELIVERY OF LIQUIDS IN PREDETERMINED AMOUNTS

Application filed October 18, 1926, Serial No. 142,499, and in Argentina August 17, 1926.

This invention relates to certain improvements in pumps for delivering liquids in predetermined amounts, particularly gasoline measuring pumps, and it has for its object an improved construction whereby the exact measuring of the amount of liquid to be delivered is obtained and any attempt to tamper with the measuring mechanism of the pump is prevented.

10 The gasoline measuring and delivering devices actually in use, operated by a plunger of fixed or adjustable stroke, offer several drawbacks. The amounts measured may be readily altered, either by mechanical means of several kinds or by fraudulent operations effected by the persons in charge of the apparatus. Besides, the measuring device never operates in an exact manner and no means are provided to insure the purchaser 15 as well as the owner the delivery of the correct amounts.

In order to overcome the difficulties above set forth, the delivering pump according to my invention is based on entirely novel principles in apparatus of this description and embodies features entirely its own.

An essential feature of the invention consists in that the counting or registering device is operated by the overflow pipe in its 20 ascending stroke.

The invention further comprises special means for locking the pump in position when the gasoline discharge valve is opened, and means for maintaining such locked condition 25 until the overflow pipe has been returned to its position at zero.

The invention also has for object means for preventing the pump from being operated when the overflow pipe does not occupy one of its predetermined levels, corresponding to predetermined measures registered by the registering device.

The invention also comprises other objects 30 which will appear in the course of this specification and will be particularly pointed out in the appended claims.

In order that my invention may be readily understood and carried into practice without difficulty, a preferred embodiment of

the same has been shown by way of example in the accompanying drawings, wherein:

Figures 1 and 2 are diagrammatic views, in side and front elevation, respectively, of the apparatus in its position of delivery, with 55 the rack and pump in their locked positions, the contents being discharged from the glass reservoir.

Figures 3 and 4 are corresponding views of the apparatus, with the rack and pump released, ready to raise the overflow pipe to 60 the desired position, and

Figure 5 is a side view of the apparatus with the pump released and the overflow pipe locked in position ready for charging the 65 transparent reservoir.

In all the said views, the same reference numerals are used to indicate like or corresponding parts.

Referring more particularly to the drawings, 1 indicates a rotary pump of any suitable type which is arranged in a feed pipe 1' leading from a source of supply (not shown) to a glass reservoir 2, the wall of which is marked at various levels to indicate different 70 quantities of gasoline to be delivered. A three-way valve 5 is arranged in the upper portion of pipe 1' to control communication between the latter and the reservoir, and between said reservoir and the discharge pipe 75 12 connected to the valve casing. The reservoir 2 is equipped with a vertically-movable overflow pipe 3 mounted in a guide tube 4 that opens at its top into said reservoir, the upper end of this pipe coating with the quantity indicia marked on the reservoir wall.

To operate the pump 1, its shaft has fixed to it a ratchet wheel 17 provided with a slotted hub engageable by a cross-pin 15 carried by an endwise-movable horizontal shaft 13, so 80 that by moving said shaft in the proper direction the pump will be clutched thereto and will be driven by the rotation of the shaft. The latter also carries a second cross pin 14 to engage the slotted hub of a pinion 16 that 85 is loose on the shaft to couple the same thereto, the arrangement being such that when one cross pin is engaged the other is disengaged. Pinion 16 meshes with and actuates a vertical rack 11 which, at its lower end, is con- 90

5 nected by a cross-piece 12 to the corresponding end of a vertical rod 30 rigidly secured at its upper end to the overflow pipe 3, in consequence whereof the rotation of shaft 13 will serve to effect the upward or downward movement of the rack and, hence, the adjustment of pipe 3, when the driving pinion and the shaft are coupled together.

10 Means are provided for locking the rack 11, and with it the overflow pipe 3, in adjusted position; and in the construction illustrated such means comprise a detent 18 in the form of a horizontal pin or finger selectively engageable in a vertical series of slots 20, 21, 15 22 and 23 formed transversely through the rack from side to side thereof at points corresponding, respectively, to the 5, 10, 15 and 20 liter marks on the wall of the glass reservoir. This detent is attached to a collar 24 which is adjustably secured to the endwise-movable shaft 13 and is set or positioned by hand to effect the engagement of the detent in the selected opening or slot in the rack.

19 A set of laterally-projecting lugs or fingers, 25 designated 7, 8, 9 and 10, is also arranged along one side face of the rack slightly above the corresponding openings in position to successively engage the operating element 6 of a register or counter (not shown) during the 30 ascent of the rack, so that such element will be turned or otherwise actuated each time it is struck by one of said lugs. The aforesaid operating element 6 is merely indicated diagrammatically, but the action which takes 35 place will readily be understood.

40 Considering so much of the apparatus as has been described, the operation is substantially as follows: In the normal position of parts, the pump 1 is uncoupled from the operating shaft, and both the detent 18 and a second detent 19 hereinafter referred to are disengaged from the rack 11, so that the latter is free to execute its upward movement when said shaft is rotated, since the pinion 16 is 45 clutched to the shaft by the same movement that unclutches the pump, or by a separate, or supplemental movement of the shaft in case the pins 14 and 15 are so spaced that both may be free from their respective hub slots 50 at the same time. Assuming, for example, that 15 liters (3 gallons) of gasoline are to be dispensed, the shaft 13 is then rotated in a direction to cause the ascent of the rack and, hence, the overflow pipe 3, until the top of the 55 latter is exactly in line with the "15" mark on the reservoir at which time the "15" opening 22 in the rack will align with the detent 18 and the operating element 6 of the counter will have been actuated three times by the 60 lugs 7, 8 and 9. Collar 24 is then moved inward to engage detent 18 in opening 22, thereby locking the rack and the overflow pipe in 65 adjusted position.

65 At the completion of this preliminary or setting operation, shaft 13 is pushed inward

70 to unclutch its pinion 16 and to couple to it, instead, the pump 1. Rotation of the shaft then drives the pump, with the result that gasoline is forced through the feed pipe 1' and the then open valve 5 into the reservoir 2 and fills the same until the level reaches the top of pipe 3, any excess gasoline being returned to the main supply through said pipe.

75 Thereafter, the controlling valve 5 is turned into a position in which it connects the reservoir with the discharge pipe 1², to deliver the gasoline to the purchaser; and this movement of the valve is also utilized to release detent 18 from the rack. For this purpose, the said valve is rigidly connected to an upper horizontal shaft 25 provided with two arms 26 and 26², the latter of which has pivoted to it the upper end of a rod or link 27 whose lower end is pivoted to one arm of a bell-crank 19'. The previously-mentioned detent 19 is pivoted to the other arm of the bell-crank and is disposed exactly in line with the detent 18, so that when the bell-crank is rocked by the rotation of the valve shaft 25, 80 said detent 19 will be moved toward the rack and will enter the opening wherein detent 18 is engaged, forcing out the latter ahead of it. Hence, detent 18 will be released, but detent 19 will continue to keep the rack locked. 85

90 At the same time, the movement of the other arm 26 on the valve shaft serves to disengage its hooked end 26' from the hook 28' on the upper end of a vertical rod or link 28 that is pivoted at its lower end to a pawl 95 lever 29, whereupon the parts 28 and 29 drop by gravity and the pawl engages ratchet 17 and locks the pump against action. 100

105 To enable a fresh operation to be carried out, the valve 5 is moved to a position to cut out communication with the reservoir, and in so doing the shaft 25 is turned in a direction to cause arm 26², rod 27 and bell-crank 19' to withdraw detent 19 from the rack which is thereby unlocked, the arm 26 being brought to vertical position. Shaft 13 is then moved outward to uncouple the pump and couple the rack, and then is turned in a direction to cause said rack to descend to its "0" position, the overflow pipe 3 likewise moving downward and to the same extent. During the last part of this movement, the cross-piece 12 to which the rack and the rod 30 are attached strikes against and depresses the adjacent end of a centrally-fulcrumed lever 31, thereby raising its other end. The latter end of this lever 31 has pivoted to it a vertical rod 32 which underlies the pawl lever 29, so that when lever 31 is rocked in the manner described, it pushes lever 29 upward and thus disengages it from ratchet 17, with the result that the pump is unlocked. The upward movement of lever 29 is transmitted to rod 28 which is thereby moved into position for re-engagement with the hooked end 110 115 120 125 130

26' of arm 26, which can be effected by turning shaft 25 slightly in the proper direction, so that the parts are now in readiness for a fresh cycle of operations.

5 Modifications and changes may obviously be made within the scope of the invention.

I claim:

1. In a liquid dispensing apparatus, a reservoir, an overflow pipe movable thereinto to different predetermined positions corresponding to different definite quantities of liquid to be dispensed, feed and discharge pipes connected with the reservoir, a pump for forcing liquid through the feed pipe into 15 said reservoir, a device for setting the overflow pipe, and a shiftable operating element to selectively operate either the pump or the setting device.

2. In a liquid dispensing apparatus, a reservoir, an overflow pipe movable thereinto to different predetermined positions, corresponding to different definite quantities of liquid to be dispensed, feed and discharge pipes connected with the reservoir, a pump 25 for forcing liquid through the feed pipe into said reservoir, a device for setting the overflow pipe, an operating shaft, and clutch means for alternatively coupling said shaft either to the pump or to the setting device.

3. In a liquid dispensing apparatus, a reservoir, an overflow pipe movable thereinto to different predetermined positions corresponding to different definite quantities of liquid to be dispensed, feed and discharge 35 pipes connected with the reservoir, a pump for forcing liquid through the feed pipe into said reservoir, a device for setting the overflow pipe, a shiftable operating element to selectively operate either the pump or the setting device, and means for positively locking the pump against action excepting when the overflow pipe occupies one of its predetermined positions.

4. In a liquid dispensing apparatus, a reservoir, an overflow pipe movable thereinto to different predetermined positions corresponding to different definite quantities of liquid to be dispensed, feed and discharge pipes connected with the reservoir, a pump 50 for forcing liquid through the feed pipe into said reservoir, a device for setting the overflow pipe, a shiftable operating element to selectively operate either the pump or the setting device, means for normally locking the pump against action, and means for releasing said locking means when the overflow pipe occupies one of the predetermined positions.

5. In a liquid dispensing apparatus, a reservoir, an overflow pipe movable thereinto to different predetermined positions corresponding to different definite quantities of liquid to be dispensed, feed and discharge pipes connected with the reservoir, a pump 65 for forcing liquid through the feed pipe into

the reservoir, a device for setting the overflow pipe, an endwise-movable operating shaft, and means carried by said shaft for coupling it to the pump when moved in one direction and to the setting device when in the other direction.

6. In a liquid dispensing apparatus, a reservoir, an overflow pipe movable thereinto to different predetermined positions corresponding to different definite quantities of liquid to be dispensed, feed and discharge pipes connected with the reservoir, a pump for forcing liquid through the feed pipe into the reservoir, means including a rack for setting the overflow pipe, an operating shaft, a loose pinion on said shaft in mesh with the rack, and clutch means on said shaft for alternatively coupling either the pump or the pinion thereinto.

7. In a liquid dispensing apparatus, a reservoir, an overflow pipe movable thereinto to different predetermined positions corresponding to different definite quantities of liquid to be dispensed, feed and discharge pipes connected with the reservoir, a pump 75 for forcing liquid through the feed pipe into the reservoir, said pump having a notched hub secured to its shaft, means including a rack for setting the overflow pipe, an operating shaft, a loose pinion on said shaft meshing with said rack and having a notched hub, and means carried by said shaft for engagement alternatively with either notched hub to couple the shaft to the pump or to the pinion.

8. Dispensing apparatus, according to claim 7, in which the coupling means consists of a pair of spaced pins carried by the operating shaft, said shaft being movable endwise in one direction to engage one pin with the hub on the pump shaft and in the opposite direction to engage the other pin with the pinion hub.

9. In a liquid dispensing apparatus, a reservoir, an overflow pipe movable thereinto to different predetermined positions corresponding to different definite quantities of liquid to be dispensed, feed and discharge pipes connected with the reservoir, a single valve to control communication between either of said pipes and the reservoir, a pump for forcing liquid through the feed pipe into the reservoir, a device for setting the overflow pipe, a device for locking the pump against operation, and a separate device for locking the setting device against operation, both locking devices being brought into action automatically consequent upon movement of the valve into position to effect communication between the reservoir and the discharge pipe.

10. In a liquid dispensing apparatus, a reservoir, a vertically-adjustable overflow pipe therein, feed and discharge pipes connected with the reservoir, a single valve to control communication between either of said pipes

and the reservoir, a pump for forcing liquid through the feed pipe into the reservoir, a device for locking the pump against operation, and a separate locking device to prevent adjustment of the overflow pipe, both locking devices being brought into action automatically consequent upon movement of the valve into position to effect communication between the reservoir and the discharge pipe.

11. In a liquid dispensing apparatus, a reservoir, a vertically-adjustable overflow pipe therein, feed and discharge pipes connected with the reservoir, a rotary valve to control communication between either of said pipes and the reservoir, a spindle whereon said valve is mounted, a pump for forcing liquid through the feed pipe into the reservoir, a gravitally-acting locking device for said pump normally held in raised position by the valve spindle but released upon rotation of the latter to drop into active position, and a second locking device also actuated consequent upon such rotation to prevent adjustment of the overflow pipe.

12. In a liquid dispensing apparatus, a reservoir having a vertical series of graduations marked therein in ascending order starting from a zero graduation located substantially level with the bottom wall of the receptacle, said wall having an opening therein; an overflow pipe movable vertically through said opening to positions alining with said graduations and having its upper edge normally at the level of the zero graduation; feed and discharge pipes connected with the reservoir; valve means for controlling communication between said feed and discharge pipes and the reservoir; a pump for forcing liquid through the feed pipe into said reservoir; a device for setting the overflow pipe; and a common operating element between said pump and setting device.

13. In a liquid dispensing apparatus, a reservoir, an overflow pipe movable thereto into different positions, corresponding to different definite quantities of liquid to be dispensed, feed and discharge connections associated with the reservoir, a pump for forcing liquid through the feed connection into said reservoir, a device for setting the overflow pipe and embodying an element connected to move in unison with said pipe, and means carried by said movable element for operatively engaging the actuating element of a counter or register a number of times depending upon the extent of its movement.

14. In a liquid dispensing apparatus, a reservoir, an overflow pipe movable thereto into different positions, corresponding to different definite quantities of liquid to be dispensed, feed and discharge connections associated with the reservoir, a pump for forcing liquid through the feed connection into said reservoir, a device for setting the

overflow pipe and embodying an element connected to move in unison with said pipe, and a set of spaced projections on said movable element for operatively engaging the actuating element of a counter or register a number of times depending upon the extent of its movement.

In testimony whereof I affix my signature.
